United States Patent Office.

JOHN T. WEBSTER, OF NEW YORK, N. Y., ASSIGNOR TO "CROSSLEY COMPANY," OF BRIDGEPORT, CONNECTICUT.

Design No. 3,685, dated September 28, 1869.

DESIGN FOR A FELT BORDER.

The Schedule referred to in these Letters Patent and making part of the same.

To all whom it may concern:

Be it known that I, JOHN T. WEBSTER, of the city and county of New York, and State of New York, have originated and designed a new Pattern for Felted Goods, or other fabrics, of which the following is a full, clear, and exact description, reference being had to the accompanying drawings, making part of this specification.

The drawings represent, between the letters A and B, three repetitions of the design, thus endeavoring to show its chief intention, viz, that of an edging or border-trimming to fur, felted, or other descriptions of carriage or lap-robés.

I claim, first, the configuration or linear arrangement substantially; and second, the configuration, in combination with the arrangement and location of the shades and colors.

What I claim as my invention, and desire to secure by Letters Patent, is—

The design or pattern for felted goods or other fabrics, herein set forth.

JOHN T. WEBSTER.
